UNITED STATES PATENT OFFICE.

ALOYSIUS JAMES CARR, OF CARTHAGE, INDIANA, ASSIGNOR TO F. X. HOOPER COMPANY, OF GLENARM, MARYLAND, A CORPORATION OF MARYLAND.

CUTTING, CREEASING, AND SLOTTING MACHINE.

Application filed June 30, 1925, Serial No. 40,591. Renewed October 12, 1927.

This invention relates to a mechanism for transversely slotting and scoring box blanks as they are moved lengthwise along a bed. The mechanism is designed particularly for 5 use as an attachment to presses for printing upon the blanks, although it may be used separately, and it may have associated with it, well known devices for effecting longitudinal scoring of the blanks, although such 10 are not shown in the drawing.

In the accompanying drawing,

Fig. 1 is a side elevation of the attachment applied to a printing press, the rear parts of the latter being shown;

15 Fig. 2 is a front elevation of the slotting attachment, looking from left to right in Fig. 1, the pull rollers being omitted;

Fig. 3 is a top plan view of the same; and,

20 Fig. 4 is a plan view of a blank showing the slots made by the attachment.

Referring to Fig. 1 of the drawing, *a* indicates a part of the frame of a printing press having a stationary bed 1, along which box blanks are moved from left to right, between a form roller 2 and an impression cylinder (not shown) on a shaft 3. The driving shaft by which power is applied to the press is indicated at 4, and this shaft carries a pinion 5, meshing with a gear 6 on the shaft 3. A gear 7 on the latter shaft meshes with a large gear 8, which drives a gear 9 on a shaft 10, the latter being mounted in a frame *b* which has a bed forming a continuation of the bed of the printing press. The 25 slotting knives are mounted upon the shaft 10, as hereinafter described. The blanks to be slotted, after passing between the form and impression cylinders, are carried to the right in Fig. 1, by pairs of pull rollers 11-12, 13-14, driven from the main shaft 4 through the train of gearing shown and unnecessary to describe. From the pull rollers 13-14, the blanks pass beneath a creasing roller 15 and then between pull rollers 16 and 17, which deliver the blanks to an 30 endless tape 18, by which they are carried away from the machine. The pull rollers 16 and 17 are operated from a gear 19 on the shaft 10 which meshes with a gear 20, to

35 which is connected a gear 21, meshing with a gear 22 on the shaft 23 of the pull roller 17. The pull roller 16 is operated from the gear 21 through a train of gearing 24-25-26 and a gear 27 on the pull roller 40 shaft 28.

Three wheels or spiders 29, 30, and 31, secured to the shaft 10, carry the slotting knives. These knives are arranged in hollow bars *c*, *d*, and *e*, which are mounted upon the spiders parallel with one another and with 45 the shaft 10. As shown in Figs. 2 and 3, threaded adjusting rods 32 and 33 extend through each end of each hollow bar, and upon each pair of rods are mounted bearings 34 which support a rock shaft 35, to which is 50 secured a segmental gear 36, and a knife 37 is secured to this gear, so that when the shaft 35 is rocked the knife will be oscillated. A rack 38 engages the segmental gear, and this rack is secured to a rod 39 which slides in an 55 opening in the end of the hollow bar and in a guide 40, within the bar. Upon the outer end of the rod 39 is arranged a roller 41, which extends into a groove 42 in the face of an annular cam *f*. This cam is stationary 60 and concentric with the axis of the shaft 10. As shown, there are two cams, secured to the opposite sides of the machine, and projecting from the ends of each hollow bar are the rods 39 with attached rollers 41, the latter 65 entering the grooves in the cams. The cams are so formed that when a knife-carrying bar is at the highest point in its revolution, the rods 39 will be drawn outwardly and the knives, which operate in slots 43 in the 70 bars, will lie in horizontal positions with the backs of the knives substantially flush with the outer surfaces of the bars. As the bars, in turning from right to left, in Fig. 1, start to ascend, the rollers are moved inwardly by the inwardly inclined portions 75 44 of the cams and the rods 39, moving inwardly, will cause the knives to rock to the radial positions shown on the bar *d* in Figs. 2 and 3. From this position, the cams turn 80 abruptly outward, as shown at 45, and the knives are thereby rocked to the horizontal position, reaching this position at about the time when the bar carrying the knives is at 85 its uppermost position.

Creaser blades 46 are arranged in each of the bars for transversely creasing the box blanks in line with the slots made by the knives.

In the operation of the mechanism, the 105 blanks pass from left to right in Fig. 1, between the printing rollers and then beneath the creasing roller 15. The peripheral speed of the outer faces of the bars carrying the knives is substantially the same as the pe- 110

ripheral speeds of the printing rollers and pull rollers and the knife carrying bars are spaced about the spiders the proper distances to cause the knives to engage the blanks 5 along the lines where the slots are desired. While the forward part of a box blank is approaching the line passing vertically through the shaft 10, the knives carried by the hollow bar *c* are closing, and in closing, 10 they cut the transverse cuts 47 in the blank *h*, Figs. 2 and 4. Immediately afterward, the creaser blade 46 in said bar presses the blank against the creaser roller 15, and the transverse crease 47^a is made in the blank. 15 The knives at this time are in horizontal position and lie below the edge of the creaser blade. Similarly, when the knife-carrying bar *d* rises to its highest point, the knives on said bar will cut the slots 48 and the creaser 20 blades will make the crease 48^a, and when the blades carried by the bar *e* reach their highest point, they will cut the slots 49 and the creaser blade will form the crease 49^a. The blank will then pass from the machine and 25 succeeding blanks will be operated upon in the same way.

The supporting bars *c*, *d*, and *e* for the knives and creaser blades will, of course, be mounted adjustably on the spiders, in order 30 that the bars may be spaced apart to suit the desired spacing of the slots and creases in the blanks.

What I claim is:

1. The combination with a bed and means 35 for moving box blanks along the bed, of a carrier rotatable about an axis transverse to the bed, knife-blades on the carrier movable in a plane containing its axis, means for rotating the carrier to carry the knives into 40 and out of position to cut the blanks and at substantially the same speed as the blanks, and means for closing the knives in the cutting position and for opening the knives after leaving said position.

45 2. The combination with a bed and means for moving box blanks along the bed, of a carrier rotatable about an axis transverse to the bed, knife-blades pivotally mounted at the sides of the carrier out of the path of 50 movement of the blanks and adapted to rock in a plane containing the axis of the carrier, means for rotating the carrier to carry the knives into and out of position to cut the blanks, and means for closing the knives in 55 the cutting position and for opening the knives after leaving said position.

60 3. The combination with a bed and means for moving box blanks along the bed, of a carrier rotatable about an axis transverse to the bed, supporting bars on said carrier parallel with its axis, means for rotating 65 the carrier to move said bars into engagement with the blanks and at the same speed and in the same direction as the blanks, knife blades pivotally mounted at the end

70 portions of the bars, means for rocking said blades to closed positions to cut the blanks when the supporting bars engage the latter and for moving the blades to open position after said bars move out of engagement with the blanks.

4. The combination with a bed and means 75 for moving box blanks along the bed, of a carrier rotatable about an axis transverse to the bed, supporting bars on said carrier parallel with its axis, means for rotating the carrier to move said bars into engagement with the blanks and at the same speed and in the same direction as the blanks, means 80 for transversely slotting the blanks when the supporting bars are in engagement therewith, creaser bars extending longitudinally of the supporting bars, and a roller cooperating with the creaser bars to transversely 85 crease the blanks after they have been slotted.

5. The combination with a bed and means 90 for moving box blanks along the bed, of a carrier rotatable about an axis transverse to the bed, supporting bars on said carrier parallel with its axis, means for rotating the carrier to move said bars into engagement with the blanks and at the same speed and in the same direction as the blanks, 95 knife blades pivotally mounted at the end portions of the bars, means for rocking said blades to closed positions to cut the blanks when the supporting bars engage the latter and for moving the blades to open position after said bars move out of engagement with 100 the blanks, creaser bars extending longitudinally of the supporting bars between the knife blades, and a roller adapted to press the blanks against the creaser bars after the blanks have been slotted.

6. The combination with a bed and means 105 for moving box blanks along the bed, of a shaft mounted transversely of the bed and below the same, supporting bars arranged parallel with the shaft and rotatable therewith, knife blades pivotally mounted on said bars, rods for rocking said blades, and stationary cams for moving said rods to rock the blades to open and closed positions.

7. The combination with a bed and means 110 for moving box blanks along the bed, of a shaft mounted transversely of the bed and below the same, supporting bars arranged parallel with the shaft and rotatable therewith, a creasing roller arranged above the 115 bed at one side of the axis of said shaft, knife blades pivotally mounted at the end portions of the supporting bars, a creaser bar between the blades on each bar, stationary annular cams, and means engaging said 120 cams for rocking the blades.

In testimony whereof I hereunto affix my signature.

ALOYSIUS JAMES CARR.
